(57) CLAIM

The ornamental design for a tension control bushing for electrical wire spools, as shown and described.

DESCRIPTION

FIG. 1 is a front perspective view of a tension control bushing for electrical wire spools, showing my new design;

FIG. 2 is a rear perspective view;

FIG. 3 is a top plan view;

FIG. 4 is a bottom plan view; and,

FIG. 5 is a front elevation view, the rear elevation view being identical thereto.
